(No Model.)

L. S. OSGOOD.
ORE CONCENTRATING TABLE.
No. 324,783. Patented Aug. 18, 1885.

UNITED STATES PATENT OFFICE.

LEONARD S. OSGOOD, OF STOCKTON, UTAH TERRITORY.

ORE-CONCENTRATING TABLE.

SPECIFICATION forming part of Letters Patent No. 324,783, dated August 18, 1885.

Application filed June 12, 1885. (No model.)

To all whom it may concern:

Be it known that I, LEONARD S. OSGOOD, a citizen of the United States, and a resident of Stockton, Tooele county, Utah Territory, have 5 invented certain Improvements in Ore-Concentrating Tables, of which the following is a specification.

My invention relates to that class of concentrating-tables used for saving gold, silver, 10 lead, and other metals and minerals; and the object is to provide a concentrator that will save the very fine "flour" gold, silver, lead, or other mineral that is usually lost by the ordinary machines and methods employed and 15 in common use at this time.

In the drawings which serve to illustrate my invention, Figure 1 is a side elevation of my improved concentrating-table. Fig. 2 is 20 a plan of the same, the central portion being broken away. Fig. 3 is a transverse section taken on line 3 3 in Fig. 1.

A is a suitable stout frame, in which is hinged at *a* a stout frame, B, which has a vertical swinging movement on its hinges at *a*. 25 The free swinging end of frame B is supported on a screw, C, which is coupled to the frame B by a hinge-bolt, *b*, and fits at its lower end in a socket in a plate, *c*, on the main frame. On the screw C is a wheel-nut, D, whereby the 30 free end of the frame B may be raised and lowered and adjusted with the greatest nicety. On the frame B are mounted rollers *d d*, the axes of which rest in open bearings in pillow-blocks *e e* on frame B. These rollers have 35 circumferential grooves in their peripheries in the manner of sheaves.

E is the concentrating-table proper, which is mounted on the rollers *d*, and is made capable of receiving an endwise reciprocating 40 movement. On the bottom of this table are V-shaped tracks *g g*, the edges of which engage the grooves in the rollers *d*. This flange construction is designed to prevent any lateral movement of the table on the rollers. The 45 table E has its upper surface covered with a metal plate, *x*, the kind of metal being that best suited to the ore treated. At the sides of the table are raised rails or flanges *h h*, and there is also a raised rail or flange, *h'*, at the 50 receiving end.

The mechanism for imparting a reciprocating

movement to the table comprises a rotatively-mounted shaft, F, and its pulley G, an eccentric, *i*, on this shaft, and an eccentric-rod, *j*, leading from the eccentric strap *i'* to the end 55 of the bed and connected thereto with a hinge-coupling. Rotation of shaft F will produce reciprocation of the bed, and the extent of this reciprocatory movement may be varied by making the throw of the eccentric adjustable in any of the well-known ways.

The ore, in pulpy or liquid form, is fed onto the table at the end opposite to the hinge *a* through a cross-pipe, *k*, provided with perforations or short jet-pipes *ll*. Any other equivalent means may be employed for delivering the ore on the table. H is an apron secured at its upper end to that end of the table opposite the feed. The refuse flows down this apron. 70

In using my machine the table is given the proper vertical adjustment. The fine ore, sand, or "slums" is fed onto the table, as described, and the table reciprocated, in order to cause all the fine particles to settle to the bottom. The 75 refuse is caused to flow off at the apron H, and the valuable product left adhering to the surface is shoveled off into any suitable receptacle for future reduction. Another charge of slums, &c., may then be run onto the table 80 and the process repeated.

The motion of the table is such that the refuse matter is carried off by the water and the heavier valuable product retained on the table. In treating gold-bearing material the 85 plate *x* on the table should be of copper, which would permit of its being amalgamated, whereby it would catch all the gold, silver, or amalgam, (as in the case of slums.) When a sufficient amount had been collected, the 90 plate would have to be cleaned off and the process repeated.

Having thus described my invention, I claim—

1. The combination, with the concentrating-table and the means, substantially as described, of imparting to it a reciprocating motion, of the hinged supporting-frame B, provided with a nut and screw for adjusting vertically its free end, the grooved bearing-rollers *d*, and 95 the tracks *g*, substantially as set forth.
2. The combination, with the concentrating-

table, the mechanism for reciprocating it, the tracks *g*, the rollers *d*, mounted on the frame *B*, the said frame *B* hinged at one end, as shown, the screw *C*, hinged at *b* under the free end 5 of frame *B*, with its end engaging a socket, *c*, and the nut *D*, all arranged to operate substantially as set forth.

3. The combination of the table *E*, provided with tracks *g* on its under side, the shaft *F*, eccentric *i*, eccentric-rod *j*, coupled to table *E*, the grooved rollers *d*, mounted on the frame *B*, the tracks *g*, resting on said rollers, the frame

B, hinged to the main frame at the end where the reciprocating mechanism of the bed is mounted, and the nut and screw for regulating the height of the free end of frame *B*, all substantially as herein set forth. 15

In witness whereof I have hereunto signed my name in the presence of two subscribing witnesses.

LEONARD S. OSGOOD.
